JOHN FOX JENNENS MALONE, OF NEWCASTLE-UPON-TYNE, ENGLAND, ASSIGNOR TO
THE SENTINEL COMPANY, LIMITED, OF NEWCASTLE-UPON-TYNE, ENGLAND.

DISTANCE-THERMOMETER.

1,284,915.

Specification of Letters Patent. Patented Nov. 12, 1918.

Application filed September 20, 1916. Serial No. 121,139.

To all whom it may concern:

Be it known that I, JOHN FOX JENNENS MALONE, a subject of the King of Great Britain, residing in Newcastle-upon-Tyne, 5 England, have invented certain new and useful Improvements in and Relating to Distance-Thermometers, of which the following is a specification.

This invention relates to improvements in 10 and relating to so-called distance thermometers in which the vessel or chamber in which it is desired to ascertain the temperature is located at a point more or less remote or inaccessible from the indicator itself and 15 in which provision is made for compensating for the expansion of fluid outside the main receptacle such provision comprising two tubes, one of which leads to the bulb within the receptacle while the other terminates 20 outside the said bulb. The tubes just above referred to have previously each been connected to indicating tubes preferably of glass of an internal diameter such that motion of the free surface of the liquid 25 therein may be of convenient amplitude.

The present invention has for its object to provide an improved thermometer of the type referred to, and in which provision is made whereby errors due to thermal 30 changes acting upon the connecting tube are avoided.

As distinguished from the known arrangements, according to this invention, I provide a central balanced column of sensitive liquid. 35 The whole system is moreover closed so that difficulties of transport are avoided. The invention further provides certain improvements whereby I am enabled to secure a large or comparatively large volume of 40 liquid, without requiring that the instrument shall be of such dimensions as to render it unwieldy.

In practice when using liquids which do not vaporize at normal atmospheric temperatures mercury for example I use a tube bent 45 in the form of a double inverted U forming an inner or middle upright U therebetween and I generally place the inner U in front of the outer legs, but they can be disposed in 50 any plane as long as the balanced central liquid is maintained. The metal compensating pipe is joined to one leg of this double inverted U tube, the metal pipe coming from the bulb is joined to the other leg of 55 the double inverted U tube. The level of

the liquid in the outer legs is above the metal and glass joint. In the inner limbs of the double inverted U tube is a separate parcel of liquid. Between the center and outer bodies of the liquid is a gas or a gaseous 60 mixture under such pressure as will secure efficient working.

In order that the invention may be the better understood drawings are appended in which:—

Figure 1 is a front elevation of a form 65 of the invention.

Fig. 2 is a side view.

Fig. 3 is a plan or a top view.

Fig. 4 is a cross sectional plan taken on 70 line BB Fig. 1.

Fig. 5 is a front view with the front of the case removed.

Fig. 6 is a side view with the side wall 75 of the case removed.

Fig. 7 is a back view with the back removed.

Referring to the accompanying drawings 19 indicates a case within which is arranged a scale 20, and a double inverted U- 80 tube formed of glass and containing a sensitive liquid. The case is provided with a cover 22 having an opening therein through which the scale and one limb of the indicating tube is visible. The case at the back 85 is provided with lugs 23 whereby it may be secured to a suitable support. 24 indicates a board or partition supporting the indicating tube, which tube in the present instance is of a double inverted U-shaped 90 outline, the rear limbs 25 being disposed in a plane behind the plane of the front limbs 26 as shown in Figs. 4 to 7, the said rear limbs being disposed at the back of the partition 24 and terminating at a point approximately in the center of the length of the other limbs. In order to obtain a large or comparatively large volume of fluid 95 without increasing the length of the U tube, whereby the instrument would be unduly 100 large and unwieldy, the bore of the limbs 25 is of somewhat larger diameter than the bore of the inner limb 26, such enlargement being obtained either by bubbles blown therein or by means of a parallel enlargement. Cleats or clips indicated by 27 are provided to retain the indicating tube in 105 position upon the partition 24. Connected in any suitable manner to the ends of the rear limbs of the tube 25 are platinum or 110

other tubes 28 which tubes in their turn are connected to other tubes 29, 30, retained in position by means of a washer and screw or any other suitable means. The tubes 29 and 30 are contained in a flexible outer tube 43 connected to the lower end of the bulb 44 by means of a union 45. The tube 30 is connected to the bulb 44 while the tube 29 is closed at the end and stops just short of the bulb 44 as shown in Fig. 1. The tubes 30 and 29 which are respectively connected to the bulb and terminate at a point outside said bulb, are filled with the liquid and the rear limbs 25 of the indicating tube, as well as the front limbs 26, are partly filled with the said liquid, the spaces above the liquid in the respective limbs being filled with a gas or gaseous mixture. The scale 20 is fixed in any suitable manner to the partition 24. In the example illustrated the limbs 25 of the tube are preferably provided with a series of bulbous enlargements indicated by 25^a, although if desired the bore may be of the same size throughout. Instead of this, however, the front portion of the tube may have a bore of less diameter than the rest of the tube for any desired portion of its length, or bulbs or bubbles can be blown in the inner U so that an amplified movement of the fluid is obtained, and between any two specified temperatures a wide open scale may be employed.

In use, if heat is applied to the bulb, the liquid therein expands, and flows up the metal pipe 30 and up one rear limb of the indicating tube, the gas is compressed and the liquid is moved in the front limbs of the tube behind one of which is the scale from which the temperature may be read off. Should heat be applied to both the tubes 29, 30 the liquid expands and rises in each of the limbs 25, equally compressing each head of gas therein, no movement of the liquid in the front limbs 26 taking place and consequently there is no change in the level thereof. Should heat be applied to the indicating part of the thermometer, the pressure of the gas will rise equally in all the limbs of the double U tube and the level of the liquid will again remain constant.

The gas being under pressure keeps the liquid in place in the limbs of the tube and consequently should the bulb be situated at a higher level than the level of the indicator the readings are not affected.

The internal diameter of the tube being small the level of the liquids is unaffected should the instrument be inclined or even turned upside down. By this means the need for special care in the packing or transport of the instrument is not required.

Claims:

1. In a distance thermometer, the combination of a rigid indicating tube comprising a rigid main U-shaped portion having its

arms bent upon themselves to form lateral U-shaped portions; a bulb; extension tubes joined to the free ends of said lateral portions and extending to the bulb, the free end of one of the extension tubes being closed 70 and the other extension tube communicating with the bulb; indicating liquid in the main U-shaped portion; sensitive liquid filling all of the bulb and extension tubes; and a compressible gas or gaseous mixture filling all 75 of both lateral portions between said fillings.

2. In a distance thermometer, the combination of a rigid indicating tube comprising a rigid main U-shaped portion having its arms bent upon themselves to form lateral U- 80 shaped portions; a bulb; extension tubes joined to the free ends of said lateral portions and extending to the bulb, the free end of one of the extension tubes being closed and the other extension tube communicating 85 with the bulb; indicating liquid in the main U-shaped portion; sensitive liquid filling all of the bulb and extension tubes; and gas filling all of both lateral portions between said fillings; all parts of said tubes and bulb being closed against communication with the atmosphere. 90

3. In a distance thermometer, the combination of a rigid indicating tube comprising a rigid main U-shaped portion having its 95 arms extending upwardly and then downwardly into downwardly extending portions; a scale associated with the arms; a bulb; extension tubes connected to said downwardly extending portions and arranged side by side the free end of one of the tubes being closed and terminating at said bulb an indicating liquid in the lower part of the U-shaped portion; a sensitive liquid filling all of the bulb and the extension tubes 100 and part of the downwardly extending portions; and gas in the upper portions of both arms indicating tubes and filling all of the interior thereof between said liquids. 105

4. In a distance thermometer, the combination of a rigid one piece indicating tube comprising a main U-shaped portion having its arms extending upwardly and downwardly to form inverted U-shaped portions and thence downward into lower portions 110 each having a series of bulbous enlargements therein; a scale disposed longitudinally of said arms; a bulb; extension tubes arranged side by side and having communication with the lower ends of said lower portions, the free end of one of the tubes being closed and terminating at said bulb, the free end of the other communicating with said bulb; an indicating liquid in the lower part of said main U-shaped portion; a sensitive liquid 115 entirely filling said bulb and said extension tubes and partly filling said lower portions; and gas in both of said inverted U-shaped portions and filling all of the interior of the one-piece tube between said liquids. 120

5. In a distance thermometer, the combination of a rigid one piece indicating tube comprising a main U-shaped portion having its arms extending upwardly and downwardly to form inverted U-shaped portions and thence downward into lower portions; a scale disposed longitudinally of said arms; a bulb; extension tubes arranged side by side and having communication with the lower ends of said lower portions, the free end of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and gas in both of said inverted U-shaped portions and filling all of the interior of the one-piece tube between said liquids. 20

6. In a distance thermometer, the combination of a rigid one-piece indicating tube comprising a main U-shaped portion having its arms extending upwardly and downwardly to form inverted U-shaped portions and thence downward into enlarged lower portions; a scale disposed longitudinally of said arms; a bulb; extension tubes arranged side by side and having communication with the lower ends of said lower portions, the free end of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and gas in both of said inverted U-shaped portions and filling all of the interior of the one-piece tubes between said liquids. 30

7. In a distance thermometer, the combination of a rigid one-piece indicating tube comprising a main U-shaped portion having its arms extending upwardly and downwardly to form inverted U-shaped portions and thence downward into lower portions; a scale disposed longitudinally of said arms; a bulb; extension tubes arranged side by side and having restricted communication with the lower ends of said lower portions, the free end of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and gas in both of said inverted U-shaped portions and filling all of the interior of the one-piece tubes between said liquids. 50

8. In a distance thermometer, the combination of a rigid one piece indicating tube comprising a main U-shaped portion hav-

ing its arms extending upwardly and downwardly to form inverted U-shaped portions and thence downward into lower portions; a scale disposed longitudinally of said arms; a bulb; extension tubes arranged side by side and having communication with the lower ends of said lower portions, the free end of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and gas in both of said inverted U-shaped portions and filling all of the interior of the one-piece tubes between said liquids; the interior of said tubes being entirely free from branches branching therefrom. 70

9. In a distance thermometer, the combination of a rigid one piece indicating tube comprising a main U-shaped portion having its arms extending upwardly and downwardly to form inverted U-shaped portions and thence downward into lower portions; a scale disposed longitudinally of said arms; a bulb; extension tubes arranged side by side and having communication with the lower ends of said lower portions, the free ends of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and gas in both of said inverted U-shaped portions and filling all of the interior of the one piece tubes between said liquids; the interior of said bulb and tubes being entirely closed from communication with the exterior atmosphere. 95

10. In a distance thermometer, the combination of a rigid one piece indicating tube comprising a main U-shaped portion having its arms extending upwardly and downwardly to form inverted U-shaped portions and thence downward into enlarged lower portions having a series of bulbous enlargements therein; a scale adjustable longitudinally of said arms; a bulb; extension tubes arranged side by side and having restricted communication with the lower ends of said lower portions, the free end of one of the tubes being closed and terminating at said bulb, the free end of the other communicating with said bulb; an indicating liquid in the lower part of said main U-shaped portion; a sensitive liquid entirely filling said bulb and said extension tubes and partly filling said lower portions; and compressed gas in both of said inverted U-shaped portions and filling all of the interior of the one-piece tubes between said liquids; the interior of said tubes being 110 120 125 130

- entirely free from branches branching therefrom; the interior of said bulb and tubes being entirely closed from communication with the exterior atmosphere.
- 5 11. In a distance thermometer, the combination of a rigid one piece indicating tube comprising a U-shaped main portion having its arms extending upwardly backwardly and downwardly to form inverted U-shaped 55 portions and continued into downwardly projecting enlarged portions provided with a series of bulbous enlargements; a scale associated with said arms; small tubes communicating with the lower ends of said 60 10 15 20 25 30 35 40 45 50 55 60 65 70 75 80 85 90 95 portions and downwardly projecting portions; a bulb; extension tubes connected to the lower ends of the small tubes and extending to the bulb, one of them communicating with the bulb and the other terminating in a closed end at the bulb; a sensitive liquid entirely filling said extension tubes and said downwardly projecting portions; an indicating liquid filling the lower part of the U-shaped main portion; and compressed gas in both of said inverted U-shaped portions and filling all of the interior of the one piece tube between said liquids; the interior of said tubes and bulbs being free of branches branching therefrom and free from communication with the exterior atmosphere.
12. In a distance thermometer, the combination of a case provided with a partition; a rigid one piece indicating tube comprising a U-shaped front portion disposed on the front of said partition and continued upwardly, rearwardly and downwardly to the rear of said partition into enlarged rear portions provided with a series of enlargements, each enlarged portion being about half the length of the front portion; a scale on said partition near said front portion; small tubes pending from and communicating with the lower ends of said rear portions; a bulb; an extension tube connecting the lower end of one of said small tubes to said bulb; a closed-end tube communicating with the free end of the other small tube and disposed close to the extension tube throughout the length of the latter to a point adjacent to the bulb; a sensitive liquid entirely filling said bulb, extension tube, closed-end tube and small tubes and partly filling said enlarged portions; an indicating liquid filling the lower part of said U-shaped front portion; and a compressed gas filling all of both arms of the one piece tube between said liquids, all parts of the interior of said tubes and bulb being free from branches and free from communication with the outside atmosphere.
- In testimony whereof I affix my signature 95 in presence of two witnesses.
- JOHN FOX JENNENS MALONE.
